TELESCOPE OR SIMILAR ARTICLE

Heinz Kraus, Altenmarkt (Alz), Germany, assignor to
Fa. Dr. Johannes Heidenhain Feinmechanik und Optik,
Traunreut, über Traunstein, Germany, a corporation
of Germany

Filed Dec. 5, 1960, Ser. No. 63,099

Claims priority, application Germany Sept. 12, 1960

Term of patent 14 years

(Cl. D57—1)

FIG. 1.

FIG. 2.

FIG. 3.

FIG. 4.

FIGURE 1 is a perspective side view of a telescope or similar article, showing my new design;

FIG. 2 is a perspective side view showing the other side thereof;

FIG. 3 is a front end view thereof; and

FIG. 4 is a top plan view thereof, the axis of the telescope being shown in a horizontal plane.

The dominant features of my new design reside in the portions shown in full lines.

I claim:

The ornamental design for a telescope or similar article, as shown and described.
